UNITED STATES PATENT OFFICE.

FRANK L. CROSS, OF WOLLASTON, MASSACHUSETTS, ASSIGNOR TO CROSS PAPER FEEDER COMPANY, A CORPORATION OF MAINE.

PAPER-FEEDING MACHINE.

1,109,902.

Specification of Letters Patent.

Patented Sept. 8, 1914.

Application filed January 2, 1912. Serial No. 668,864.

To all whom it may concern:

Be it known that I, FRANK L. CROSS, a citizen of the United States, residing at Wollaston, in the county of Norfolk and 5 State of Massachusetts, have invented certain new and useful Improvements in Paper-Feeding Machines; and I do hereby declare the following to be a full, clear, and exact description of the invention, such as will enable others skilled in the art to which it 10 pertains to make and use the same.

The invention relates to paper feeding machines which separate individual sheets from the pile or bank and feed them in 15 regular succession to a printing press or other machine for operating on or manipulating the sheets.

The object of the invention is to provide a novel and improved sheet feeding mechanism for securing the uninterrupted delivery of any desired number of sheets in regular succession so that the delays incident to reloading the feed table of the pile feeders heretofore in common use may be 20 avoided, with a resulting increase in the production of the machine to which the sheets are fed.

To this end the invention contemplates the provision of two or more mechanisms for 25 separating and feeding the sheets in regular succession, and means for discontinuing the action of that mechanism which is active and starting an inactive mechanism to continue the feeding of sheets in regular succession. With this construction the attendant may replenish and adjust the sheet supply of one feeding mechanism while another feeding mechanism is feeding sheets, and when the sheet supply of the active mechanism is exhausted this mechanism may be 30 stopped and the inactive mechanism started, so that the first sheet fed by the latter mechanism follows the last sheet fed by the other mechanism in the regular succession. The 35 stopping of one feeding mechanism and the starting of another may be effected manually, although it is preferred to do this automatically when the sheet supply of an active mechanism is exhausted. The broader features of the invention contemplate the use of 40 any suitable form of sheet separating and feeding devices, and any suitable mechanism for presenting a pile or bank of sheets to the separating devices. The invention may be 45 embodied with special advantage, however,

in machines in which the sheet supply is supported in a vertical pile upon a vertically movable table, and certain features of the invention relate to a feeding mechanism of the vertical pile type.

The various features of the invention will be readily understood from an inspection of the accompanying drawings and the following detailed description of the mechanism illustrated therein.

In the drawings Figure 1 is a front side elevation of the forward end of a sheet feeding mechanism embodying the invention in its preferred form; Fig. 2 is a similar view of the center portion of the mechanism; Fig. 3 is a similar view of the rear portion of the mechanism; Fig. 4 is a rear end elevation of the mechanism shown in Fig. 3; Fig. 5 is a sectional detail showing the devices for throwing the feeding mechanisms into and 50 out of action; Fig. 6 is a rear side elevation of the center portion of the mechanism; Fig. 7 is a plan view of the part of the mechanism shown in Fig. 2; Fig. 8 is a similar view of the part of the mechanism shown in Fig. 6; Figs. 7 and 8 constituting together a complete plan view of the center portion of the mechanism; Fig. 9 is a sectional front elevation of that portion of the machine illustrated in Figs. 2 and 6; Fig. 10 is a detail front elevation of one of the 55 clutches for driving the cam shafts of the feeding mechanisms; Fig. 11 is a sectional detail of the part shown in Fig. 10; Fig. 12 is a detail showing the guides at the front 60 of the feed tables; Fig. 13 is a detail of one of the supporting arms of the feed mechanisms; Fig. 14 is a detail elevation of the center bracket of the supporting frame for the feed mechanism; and Fig. 15 is a detail 65 elevation on an enlarged scale of one of the cut-out mechanisms for controlling the raising of the comber wheels.

In the drawings the invention is shown embodied in a machine especially designed 70 for feeding sheets to the front gages of a printing press. The machine illustrated is provided with two sheet feeding mechanisms, and with delivery devices adapted to direct the sheets fed by either mechanism 75 into position at the front gages of the press. Each sheet feeding mechanism comprises a vertically movable feed table adapted to support a pile of sheets and present the top 80 of the pile in position to be acted upon by 85

the sheet separating devices. The sheet separating devices illustrated are of common type, and consist of two constantly driven comber wheels which are simultaneously lowered upon the pile and are independently raised by cut-out devices thrown into operation by the edge of the top sheet advanced by the comber wheels. The mechanism for operating and controlling the comber wheels is similar in general construction and mode of operation to the corresponding mechanism shown and described in applicant's prior Patent No. 812,260, February 13, 1906. In the construction shown each comber wheel 1 is secured to a shaft 2 supported in arms 3 which are secured to a rock shaft 4. The comber shaft 2 is continuously driven through gearing 5 connecting the shaft with a short shaft 6 mounted in bearings in the side frame. The outer end of the shaft 6 carries the gear 7 which engages a gear 8 secured to a shaft 9. The shaft 9 extends transversely across the machine and is provided with gears 8 on each end which are respectively connected to drive the comber wheels at the corresponding side of the machine. The shafts 9 of the two feeding mechanisms are connected to rotate in unison by a sprocket chain 10 passing over sprocket wheels 11 secured to the shafts, and the shafts are driven in unison with the parts of the printing press through a gear or sprocket wheel 12 secured to the lower shaft. The comber wheel is lowered upon the pile of sheets at regular intervals by a cam 13 engaging a roll 14 carried by a link 15, one end of which is connected to an arm 16 on the rock shaft 4, and the other end of which is bifurcated to straddle the hollow cam shaft 17. When the comber wheel is in engagement with the pile it combs forward the sheets until the front edge of the sheet is in position between the delivery roll 18 and the drop roll 19 when the front edge of the sheet operates the cut-out devices through which the comber wheel is raised. These devices comprise a spring 20, one end of which is connected to the frame, and the other end of which is connected to one arm of a bell crank lever 21 which is loosely mounted on the cam shaft 17. A collar 22 is pivoted to the upper end of the lever 21 and surrounds a rod 23 which is connected to an arm 24 on the rock shaft 4. The rod 23 also carries a collar 25 arranged to be engaged by the collar 22 when the bell crank lever 21 is moved by the spring 20 in a direction to raise the comber wheel. The rod 23 also carries a spring 26 arranged between the collar 22 and an adjustable collar 27 on the rod, and adapted to force the comber wheel against the pile when the bell crank lever 21 is locked in position to stretch the spring 20, as indicated in the upper feed

mechanism in Fig. 9. During the combing the bell crank lever 21 is held in position against the tension of the spring 20 by a latch 28 engaging the lower end of the lever, as indicated in Fig. 15. The latch 28 is formed on an arm 29 which is pivotally supported upon a stud 30 carried by the bracket 31. The arm 29 also supports the rock shaft 32 which carries the trip finger 33 and the pawl 34. The trip finger 33 is arranged in the path of the sheet, and when the front edge of the sheet engages this finger it swings the pawl 34 into engagement with the teeth 35 on the constantly rotating disk 36. When the pawl is engaged with the teeth of the disk the disk forces the pawl downward and toward the left in Fig. 15, thus disengaging the latch 28 from the lower end of the lever 21 and releasing the lever. The spring 20 now swings the upper end of the lever toward the right so that the collar 22 on the lever engages the collar 25 on the rod 23, forcing the rod to the right and raising the comber wheel so that the combing action of the wheel ceases. When the comber wheel is thus raised a presser foot 37 is lowered upon the top of the pile and holds the sheet at this side from displacement in case the comber wheel at the other side of the sheet continues in action. The presser foot 37 is in the form of a lever pivoted on the rock shaft 4 and provided with a lug 38 overlying a laterally projecting pin 39 in the end of an arm 40 of the bell crank lever 21. When the comber wheel is raised by the cut-out mechanism the arm 40 swings downward so that the presser foot engages the top of the pile. After the top sheet has been advanced into position between the delivery rolls by the comber wheels the drop rolls 19 are lowered upon the sheet and the sheet is drawn from the top of the pile and carried forward to the printing press. Just before the drop rolls are lowered the cut-out mechanism is reset and the arm 40 raises the presser foot 37 from the pile. The means for resetting the cut-out devices consist of a cam 41 arranged to engage a roll 42 on the lower end of the lever 21 and a cam 43 arranged to engage a roll 44 on the end of an arm 45 which projects from the hub of the latch arm 29. The cam 43 is secured to the cam shaft 17, and the cam 41 is mounted on the stud 30 and is driven from the cam shaft by gearing 46. The cam 41 rocks the lever 21 into the position indicated in Fig. 15 after the combing has ceased and just before the drop rolls are lowered to deliver the top sheet. The cam 43 acts to hold the arm 29 in such position that the trip finger 33 does not drag along the surface of the sheet until the top sheet has been delivered, and then allows the arm to swing into position to latch the lever 21 before the comber wheel is again lowered upon the

pile. When the cut-out mechanism is reset, as above described, the comber wheel is held in its raised position until after the delivery rolls have delivered the top sheet by the cam 5. 13. When the lever 21 of the cut-out mechanism is reset it compresses the spring 26 so that this spring will act to force the comber wheel against the pile when the comber wheel is lowered, the pressure upon the pile 10 depending upon the adjustment of the collar 27.

When the drop rolls 19 are lowered to deliver the top sheet, the second sheet and the sheets beneath it are held by a tail clamp 15 47 arranged near the rear end of the pile and adapted to be raised and lowered at the proper time. The tail clamp is secured to a shaft 48 supported in arms 49 and provided with a vertical arm 50 connected by 20 a link 51 to a fixed pivot 52. The arms 49 are secured to a rock shaft 53 and one of the arms is provided with a ratchet segment 54 arranged to be engaged by a pawl 55. The pawl is mounted in a pawl carrying lever 56 and is arranged to ride over a fixed guard 57 so that the pawl is disengaged from the ratchet when the clamp is lowered upon the pile and will allow the clamp to accommodate itself to the height 30 of the pile. The pawl carrying lever 56 is actuated by a vertically moving bar 58 which underlies a roll 59 on the lever. The rear end of the bar is pivoted to the free end of a swinging arm 60 and the front end is pivoted to an arm 61 secured to a rock shaft 62. The rock shaft 62 is provided with a second arm 63 which is connected by a link 64 with an arm 65 secured to the end of the rock shaft 66. The rock 40 shaft 66 is the shaft which carries the arms 67 in which the drop rolls 19 are pivoted, and this shaft is rocked at proper intervals to raise and lower the drop rolls and to lower and raise the tail clamps by a cam 45 68 secured to the cam shaft 17 and engaging the end of an arm 69 secured to the rock shaft.

The sheets fed by the lower feed mechanism are conveyed to the front gages 70 of 50 the printing press 71 by tapes 72 which pass over the delivery rolls 18, and supporting and guiding rolls 73, 74, 75 and 76. The tapes feed the front edge of the sheet into position against the front gages and into 55 position to be acted upon by the side register devices 77, which may be of any suitable construction and may be operated in the manner fully explained in the patent above referred to. Pressure rollers 78 are 60 arranged to coöperate with the tapes as they pass over the supporting rolls 73, and these rolls may be raised and lowered at certain intervals if found desirable by any suitable mechanism. The sheets fed by the 65 upper feed mechanism are delivered to the

rolls 78 and tapes 72 by tapes 79 passing over the delivery rolls 18 and over supporting and guiding rolls 80 and 81. The delivery rolls 18 are secured upon shafts 81', and these shafts are continuously driven 70 from the gears 8 through gearing 82' shown in Fig. 2.

The feed board 82 on which the pile of sheets is carried is supported at its rear end upon a shaft 83 and is supported near 75 its front end upon a cam 84 through which vertical movement is imparted to the table to keep the top of the pile in proper position to be acted upon by the comber wheels. The table may be adjusted to move the pile 80 bodily toward or from the delivery rolls by pinions 85 formed on the shaft 83 and engaging racks 86 secured to the under side of the table. In order that the sheets at the top of the pile may be properly guided 85 over the lower delivery rolls 18, guide bands 87 are arranged to extend from a cross plate 88 at the front end of the pile to a series of disks 89 which are loosely mounted on the shaft 81' of the delivery rolls 18 and 90 are weighted to hold the bands taut. The cross plate 88 is connected with side plates 90 which are guided in ways 91 secured to the side frames, and the plates 90 are provided with vertical guideways 92 for receiving pins 93 which project from the sides of the feed table. By this construction the front plates 88 are arranged to move with the feed table when it is moved to adjust the pile toward and from the delivery rolls, 100 and at the same time the feed table is free to move vertically to maintain the top of the pile at the proper height. When the feed table is moved forward or back, the disks 89 are rotated to accommodate the 105 movement of the table and to keep the guide bands 87 taut and in proper position to direct the top sheets of the pile from the top of the plate 88 to a position between the delivery rolls. 110

As the sheets are separated and fed from the top of the pile the feed table 82 is gradually moved upward to keep the top of the pile at a substantially uniform height and in proper position to be acted upon by the 115 comber wheels. The mechanism for thus moving the feed table comprises the cam 84 and a pawl and ratchet mechanism for operating the cam, the action of which is controlled from the top of the pile. As shown, 120 the pawl and ratchet mechanism comprises a ratchet wheel 94 secured to the shaft 95, which carries the cam 84, and a pawl 96 carried by a lever 97 which is pivoted on the shaft 95. The pawl carrying lever is connected by a link 98 with a crank pin 99 on one of the continuously rotating gears 8. The pawl is normally held out of engagement with the ratchet by a guard lever 100 having a guard surface arranged to underlie 125 130

a pin 101 on the pawl. The guard lever is provided with a weight 102 which causes the lever to move with the pawl as it is reciprocated and to maintain the pawl out of engagement with the ratchet. One of the rock shafts 4 for raising and lowering the comber wheels is provided with an arm 103, the free end of which is adapted to move into the path of the lever 100 when the comber wheel 10 is lowered below a predetermined point. When the top of the pile is below this point, the arm 103 is moved into the path of the guard lever 100 when the pawl is in its retracted position indicated in Fig. 6, so that 15 when the pawl advances the guard lever is held in its retracted position and the pawl rides off the guard lever and engages the ratchet wheel. When this occurs the cam 84 is advanced to raise the pawl.

20 The cam shafts 17 which carry the cams for controlling the operation of the sheet separating and feeding devices are driven through clutches which are constructed and arranged to drive each cam shaft in the same 25 timed relation to the printing press or other machine to which the sheets are fed, and means is provided for throwing one clutch into operation when the other is thrown out, so that the change from one feed 30 mechanism to the other may be effected without interrupting the feed of the sheets in regular succession to the printing press. As shown, each clutch comprises a driving arm 104 projecting from the hub of the continuously running sprocket wheel 11, and a pawl 105 carried by a disk 106 which is secured to the hollow cam shaft 17. The pawl 105 is pivoted at 107 on the disk 106, and is held in position to be engaged by the driving arm 35 40 by a spring 108. The pawl is provided with a tail piece 109 which projects beyond the periphery of the disk 106, and is provided with a slot engaged by a pin 110 which determines the position of the pawl when it is 45 drawn radially inward by the spring 108.

The devices for throwing each clutch into and out of operation comprise a roll 111 carried by the upper end of a lever 112 which is pivoted on a bearing 113 surrounding the delivery roll shaft 81. The lever 112 may be 50 swung about its bearing to bring the roll 111 into or out of the path of the projecting tail 109 of the pawl 105. When the lever is 55 swung into position to engage a stop pin 114 the roll 111 is brought into the path of the pawl, and when the tail of the pawl strikes the roll the pawl is disengaged from its driving arm 104, and the rotation of the corresponding cam shaft 17 is immediately arrested by the friction brake 115. When the 60 lever is swung into position against the stop pin 116 the pawl 105 is released and immediately swings into position to be engaged by its driving arm 104. When one of the levers 65 112 is actuated to disengage the correspond-

ing clutch and thus render the feeding mechanism inactive, a stop arm 117 is moved into position below a roll 118 carried by an arm 119 secured to the drop roll rock shaft 66 so that the lowering of the drop rolls is prevented. The stop arm 117 is formed on a disk 120 which is mounted on the bearing 113 and is connected with the lever 112 by a spring-pressed latch 121. The latch is provided with a handle 122 through which the attendant may operate the latch to disconnect the lever 112 from the disk 120, in case he desires to throw the cam shaft of the feeding mechanism into operation without allowing the drop rolls to be lowered to deliver 80 the sheet which may be fed forward into position between the drop rolls.

In order that one feeding mechanism may be thrown into operation when the other is thrown out of operation, the starting and stopping devices are so connected that movement of either into position to disengage its clutch may move the other into position to engage its clutch. In the construction shown this connection means consists of a link 123 so connecting the disks 120 that the movement of either lever 112 causes a movement of the other lever 112 in the opposite direction, provided that the levers are connected to the disks by the latches 121. The parts are so arranged and timed that the driving clutch is disengaged and the cam shaft stopped after the comber wheels and presser foot 37 have been raised, and just before the drop rolls are lowered to carry 100 away the sheet which has been fed into position between the delivery rolls by the comber wheels. This position of the parts is shown in the lower feeding mechanism of Fig. 9. When one of the feeding mechanisms is stopped with the parts in this position the other mechanism is thrown into operation, and since the clutches are similarly arranged and timed, the cycle of operations begun by the mechanism which is 105 stopped is completed by the mechanism which is started. That is to say, the drop rolls of the mechanism which is started are lowered to feed forward a sheet at the time that the drop rolls of the mechanism which 110 is stopped would have been lowered had this mechanism continued in action. The feed of the sheets in regular succession, therefore, may be continued without interruption, although one feeding mechanism is stopped 115 and the other one started. The stopping of one feeding mechanism and the starting of the other may be effected by the attendant at any time during the operation of the machine by manipulation of either of the levers 120 125 112. Means is also provided for automatically stopping either feeding mechanism and starting the other when the supply of sheets on the feed table of the active mechanism is substantially exhausted. This means in the 130

construction shown comprises a disk 124 secured to the end of the table feeding cam shaft 95, and provided with a projecting tooth 125 for engaging a shoulder 126 on one end of a link 127, the other end of which is pivoted to the stop lever 112. The tooth 125 is so arranged that it will engage the tooth 126 during the feeding movement of the cam shaft which raises the feed table 10 into its highest position, as indicated in the lower feed mechanism of Fig. 9. This feed of the table lifting cam takes place during the operation of the comber wheels, and the tooth 125 draws the link 127 toward the 15 right in Fig. 2, thus bringing one of the stop rolls 111 into stopping position and shifting the other from stopping position to starting position. As the link 127 completes its movement toward the right, its inclined 20 free end rides up a pin 128, thus disengaging the tooth 126 on the link from the table 125. The position of the parts just after the lower link 127 has been shifted to stop the lower feed mechanism and to start the upper 25 feed mechanism is indicated in Fig. 2. After the lower feed mechanism has been thus automatically stopped and the upper feed mechanism started to continue the feed of the sheets to the printing press in regular 30 succession, the lower feed table may be lowered into position to receive a fresh supply of sheets. After placing the pile of sheets upon the feed table, the attendant may adjust the pile to bring it into proper relation 35 to the comber wheels. He may also disconnect the starting lever 112 from the disk 120 by operating the latch 121 and then shift the roll 111 out of engagement with the pawl 105, thus starting the cam shaft of 40 the lower feeding mechanism and throwing the comber wheels into operation to comb out and feed forward the top of the pile. This manipulation of the lower lever 112 does not affect the upper feeding mechanism, 45 since the connection between the lower lever 112 and the upper lever is broken by disengaging the latch 121. No sheets are carried forward by the delivery rolls of the lower mechanism at this time, since the arm 50 117 remains in position to prevent the lowering of the drop rolls 19 into engagement with the lower delivery rolls 18. Thus by proper manipulation the attendant may load the lower feed table, adjust the pile in 55 proper relation to the delivery rolls and comber wheels, and allow the comber wheels to operate until they have positioned the top sheet properly between the delivery rolls and in position to be carried forward to the 60 printing press when the drop rolls are lowered in starting the lower feed mechanism into operation. Having thus properly adjusted the lower feed mechanism the attendant brings the lever 112 into stopping

position and re-connects it with the disk 120. 65 Now when the supply of sheets upon the upper feed table is practically exhausted the upper feed mechanism will be automatically stopped and the lower feed mechanism started to continue the feed of the sheets to 70 the printing press. Now in the same manner the supply of sheets on the upper feed table may be replenished and the mechanism manipulated and adjusted to bring the top 75 of the pile into proper position with the front edge of the top sheet between the delivery rolls.

While it is preferred to employ the form of separating and feeding devices, and the construction and arrangement of parts 80 shown and described, it will be understood that this is not essential, and that the form of separating and feeding devices, and the construction and arrangement of parts, may be varied and modified without departing 85 from the broader features of the invention.

Having explained the nature and object of the invention, and specifically described one form of mechanism in which it may be embodied, what I claim is:—

1. A paper feeding machine, having, in combination, a plurality of mechanisms for separating and feeding sheets in regular succession, and means for discontinuing the action of one mechanism and starting an inactive mechanism to continue the feed of sheets in the regular succession, substantially as described. 95

2. A paper feeding machine, having, in combination, a plurality of feed tables, sheet 100 separating mechanism for each table, and means for stopping the action of one separating mechanism and starting another to continue the feeding of sheets in regular succession, substantially as described. 105

3. A paper feeding machine, having, in combination, a plurality of sheet separating mechanisms, devices for delivering the sheets from either mechanism to a common point, and means for stopping one separating 110 mechanism and starting another to continue the delivery of sheets in regular succession, substantially as described.

4. A paper feeding machine, having, in combination, a plurality of sheet separating mechanisms, devices for delivering the sheets from either mechanism to a common point, and mechanism for automatically stopping an active mechanism and starting an idle 115 mechanism to continue the delivery of sheets 120 in regular succession, substantially as described.

5. A paper feeding machine, having, in combination, a plurality of vertically movable feed tables, sheet separating devices for 125 each table, devices for delivering the sheets from either separating mechanism in regular succession, and means for discontinuing the

feed of sheets from one table and starting the feed of sheets from another table, substantially as described.

6. A paper feeding machine, having, in combination, a plurality of vertically movable feed tables, sheet separating devices for each table, devices for delivering sheets from either separating mechanism in regular succession, and means for automatically discontinuing the feed of sheets from one table when it reaches a predetermined height and for starting the feed of sheets from another table, substantially as described.

7. A paper feeding machine, having, in combination, two feed tables, sheet separating devices for each table, delivery devices for each table delivering to a common point, means for discontinuing the feed of sheets from either table, and means for starting the feed from the other table to feed the first sheet in the regular succession behind the last sheet of the discontinued feed, substantially as described.

8. A paper feeding machine, having, in combination, two sheet separating mechanisms, delivery devices for each mechanism delivering the sheets to a common point, devices for starting and stopping each separating mechanism, devices for preventing the operation of the delivery devices, and means for operating the starting and stopping devices of each mechanism independently of the corresponding delivery preventing devices, substantially as described.

9. A paper feeding machine, having, in combination, two feed tables, sheet separating devices for each table, devices for delivering the sheets from each table to a common point, mechanism for raising each table, and mechanism controlled from the table raising mechanism for stopping the feed of sheets from that table and starting the feed from the other table, substantially as described.

10. A paper feeding machine, having, in combination, a plurality of sheet separating mechanisms, devices for delivering the sheets from either mechanism to a common point, and means for stopping a separating mechanism and means for starting another separating mechanism to continue the delivery of sheets in regular succession, substantially as described.

11. A paper feeding machine, having, in combination, a plurality of sheet separating mechanisms, sheet registering mechanism, sheet conveying mechanisms for conveying sheets from either separating mechanism to the registering mechanism, and means for stopping one separating mechanism and starting another to continue the feed of

sheets to the registering mechanism in regular succession, substantially as described.

12. A paper feeding machine, having, in combination, a plurality of vertically movable feed tables, sheet separating devices for each table, sheet registering mechanism, mechanism for conveying sheets from each separating mechanism to the registering mechanism, means for discontinuing the feed of sheets from one table and for starting the feed of sheets from another table to feed the first sheet in regular succession to the registering mechanism behind the last sheet fed thereto by the discontinued feed, substantially as described.

13. A paper feeding machine, having, in combination, a plurality of sheet supporting feed tables, combing wheels and sheet operated cutouts for each table, sheet registering mechanism, delivery devices for conveying the sheets from each cutout to the registering mechanism, means for discontinuing the feed of sheets from one table and for throwing the comb wheels and delivery devices for another table into action to continue the feed of sheets to the registering mechanism in regular succession, substantially as described.

14. A paper feeding machine, having, in combination, a plurality of sheet supporting tables, comb wheels and sheet operated cutouts for each table, sheet registering mechanism, delivery devices for conveying the sheets from each cutout to the registering mechanism, means for throwing one set of comb wheels and delivery devices out of action and another set into action to continue the feed of sheets to the registering mechanism in regular succession, and means for throwing the inactive comb wheels into action while retaining the inactive delivery devices out of action, substantially as described.

15. A paper feeding machine, having, in combination, a plurality of sheet supporting tables, sheet separating devices for each table, front and side register devices, delivery devices leading from the front of each table to the registering devices, means for throwing the active sheet separating and delivery devices out of action and for throwing a set of inactive sheets separating and delivery devices into action to complete the cycle begun by the set of separating and delivery devices which are thrown out of action, substantially as described.
